UNITED STATES PATENT OFFICE.

THOMAS JEFERSON MORRIS, OF KENOMA, MISSOURI.

MOTOR FOR ROCKING CRADLES OR CHAIRS.

SPECIFICATION forming part of Letters Patent No. 362,850, dated May 10, 1887.

Application filed November 8, 1886. Serial No. 218,321. (No model.)

To all whom it may concern:

Be it known that I, THOMAS JEFERSON MORRIS, of Kenoma, in the county of Barton and State of Missouri, have invented certain new and useful Improvements in Motors for Rocking Cradles or Chairs; and I do hereby declare the following to be a full, clear, and exact description of the invention, such as will enable others skilled in the art to which it pertains to make and use it, reference being had to the accompanying drawing, which forms part of this specification.

My invention relates to an improvement in motors for rocking cradles and chairs; and it consists in the combination of the inclosing-case, which is adapted to be secured to the rocker of a cradle or chair, the shaft journaled therein and carrying a ratchet-wheel, and an operating-wheel provided with radial teeth, and which is loosely placed upon the shaft, and having a pawl which engages the ratchet-wheel, with the spring-actuated stop or detent, which is made to intermittently engage the radial teeth of the operating-wheel, and a lever which is pivoted near its inner end to the inclosing-frame and adapted to be operated upon by the radial teeth of the operating-wheel and its outer end to rest upon the floor, a rod which is secured to the lever and adapted to raise the spring-actuated stop or detent and allow one of the radial teeth of the operating-wheel to pass, and a spring for rotating the shaft and operating-wheel, all of which will be more fully described hereinafter.

The object of my invention is to provide a device which can be readily and quickly secured to the rocker of a cradle or chair by means of set-screws, and which, when wound up, will impart a rocking movement to the cradle or chair to which it is applied.

The accompanying drawing represents a device embodying my invention applied to a cradle, the case being broken away.

A represents the inclosing-case, in which is journaled the shaft B, which has rigidly secured to it the ratchet-wheel C. A coiled spring, D, of any suitable length, has its inner end secured to the shaft and its opposite end to the case for the purpose of imparting a rotary motion to the shaft in the usual manner. Loosely placed upon the shaft is the operating-wheel E, which is provided with a

spring actuated pawl for engaging the ratchet-wheel, and thus made to revolve with the shaft. One end of the shaft is made to extend through the inclosing case for the purpose of having a key applied thereto and the spring wound up.

The operating-wheel E is provided with radial teeth G for the purpose of engaging the inner end of the lever H, and to cause it to turn upon its pivot. This lever H is pivoted near its inner end, and has its outer end extended outward a suitable distance and resting upon the floor, and provided with a friction-wheel, I, for the purpose of reducing friction. Secured to the lever is the rod J, which as the lever H is made to rock alternately raises the stop or detent K. This stop or detent is pivoted at one end and extends partially around the inclosing-case immediately over the operating-wheel, and is provided with a downwardly-projecting tooth, L, for engaging the radial teeth of the operating-wheel. The spring M keeps the tooth L in engagement with the radial teeth of the operating-wheel and prevents it from revolving until the detent is raised by the upward movement of the rod J. The two sides of the inclosing-case have the projecting portions N for the purpose of extending downward upon opposite sides of the rocker, and are then secured thereto by means of set-screws. Thus it will be seen that the device can be quickly and readily attached to and detached from the rocker of an ordinary cradle or chair.

The operation of my invention is as follows: The spring is wound up, which forces the operating-wheel around into the position shown, when it is stopped by the stop or detent K. In order to start the machine, it is only necessary, after the spring has been wound, to rock the cradle toward the lever, which rests upon the floor, causing it to turn upon its pivot, and the rod J to engage the detent K and push it upward, which disengages the detent from the teeth of the operating-wheel and allows the wheel to revolve, bringing one of the radial teeth in contact with the inner end of the lever H, which forces the outer end of the lever downward upon the floor and causes the cradle to tilt until the tooth which is engaging the lever passes its inner end and leaves it free to be forced back by the momentum of the

cradle. When in this position, the stop or 5
detent again engages one of the teeth of the
operating-wheel and holds it in this position,
allowing the momentum of the cradle when
rocking back to bring the lever back into the
position shown in dotted lines, thereby pushing
the rod J upward, disengaging the stop or
detent, which again allows the wheel E to op-
erate upon the inner end of the lever and force
its outer end downward upon the floor, caus-
ing the cradle to again tilt, and this operation
is repeated until the spring is unwound. The
lever H is pivoted in such relation to the op-
erating-wheel that it is held by the detent K.
15 Its inner end will freely pass the tooth which
has just operated upon it, and the momentum
of the cradle will bring it in position to be
operated by the next tooth.
I am aware that motors have heretofore
20 been produced in which a lever is shown ex-
tending out from the operating mechanism,

and which bears upon the floor at its outer end
and operates a pawl that engages with the op-
erating-wheel, and this I disclaim.

Having thus described my invention, I 25
claim—

The combination of the outer inclosing-case,
which is made to extend downward on oppo-
site sides of the rocker and secured thereto by
means of set-screws, the operating-wheel, the 30
lever H, the stop or detent K, and the rod J
for operating the stop or detent, said lever be-
ing provided at its outer end with a wheel,
and a spring for revolving the operating-wheel,
substantially as shown and described. 35

In testimony whereof I affix my signature in
presence of two witnesses.

THOMAS JEFERSON MORRIS.
